W. H. IMPOL

SIGN HOLDER

Filed Dec. 30, 1922

INVENTOR

UNITED STATES PATENT OFFICE.

WOLDMAR HEINRICH IMPOL, OF NEW YORK, N. Y.

SIGN HOLDER.

Application filed December 30, 1922. Serial No. 609,784.

To all whom it may concern:

Be it known that I, WOLDMAR HEINRICH IMPOL, a citizen of the United States, residing at New York, in the county of New York and State of New York, have invented certain new and useful Improvements in Sign Holders, of which the following is a specification.

This invention relates to improvements in sign holders and more particularly to devices for supporting license tags and the like.

The principal object of the invention is to provide a holder for interchangeably supporting sign plates so that they may be readily removed and replaced.

Another object of the invention is to provide means to prevent rattling and chattering of the sign plates within the supporting frame and the noise resulting therefrom.

These and other objects are attained by the use of the device described in the following specification, and illustrated in the accompanying drawing, in which:

Figure 1 is a front view of a motor vehicle showing the improved sign holder attached thereto.

Figure 2 is an enlarged front view of the holder, showing the sign removed.

Figure 3 is a sectional view on line 3—3 of Fig. 2.

Figure 4 is a fragmentary rear view of the holder.

Figure 5 is an enlarged fragmentary sectional view through the holder showing in detail the sign retaining cap member.

Figure 6 is a rear view of Figure 5.

Reference being had to the drawing in detail, 10 designates in its entirety my sign holder which comprises a back plate 11 having secured to its lower and side edges the channel members 12 forming retaining elements for engagement with the bottom and side edges of the license plate 13.

Secured to the rear face, near opposite ends of the plate 11 are straps 14, the upper ends of which are bent angularly as at 15 and carry clamps 16, adapted to engage a suitable supporting element, such as rod 17.

Attached adjacent the upper edge of the

plate 11 are spring hinges 18 supporting the channel member 19 which cooperate with the channel members 12 in forming a complete frame for the license plate.

As illustrated in Figure 6, the spring 55 hinges normally tend to hold the channel 19 in closed position, and consequently retain the license plate 13 in place.

In order to avoid all unnecessary noise and clattering of the license plate within 60 the frame, there is provided a pair of leaf springs 20, secured to the front face of the plate 11 so as to normally urge the license plate 13 against the forward flanges of the channel members 12 and 19.

The spring hinges 18 above referred to comprise a base plate 21 provided at its upper end with an angularly extending arm 22, at the ends of which are formed the up-standing ears 23 and 24, pierced to receive 70 a pintle 25.

Cooperating with the hinged element above described is a hinge element comprising a base plate 26 formed at opposite ends and adjacent its lower edge with outwardly extending ears 27 and 28 which are adapted to fit between the ears 23 and 24 respectively, and like the ears 23 and 24, are pierced to receive the pintle 25 aforementioned.

Coiled about the pintle 25 is a torsional spring 30 formed at the opposite ends with oppositely extending tangential arms 31 bearing against the plates 21 and 26 as clearly shown in Figure 6.

The clamps 16 above referred to comprise clamp cooperative jaws 32 pierced to receive a clamp bolt upon which is threaded a thumb nut 33 by which the jaws 32 may be tightly drawn together about the support 90 rod 17.

It will thus be seen that there has been provided a particularly simple and efficient means for interchangeably supporting license plates on motor vehicles and it is to 95 be understood that there may be made such minor changes in the details of construction, combination and arrangement of parts as will fall within the scope of the invention as claimed.

Having thus described my invention, what I claim as new and desire to secure by Letters Patent, is:—

A sign holder comprising a plate, means for supporting said plate, channel members rigidly secured to three sides of said plate, a channel member hingedly connected to the

upperside of said plate, and spring means normally urging the last named channel member into co-operation with the first ¹⁰ named channel members to retain a sign in place.

In witness whereof I affix my signature.

WOLDMAR HEINRICH IMPOL.
